UNITED STATES PATENT OFFICE.

JOSEPH LERNOWITZ, OF NEW YORK, N. Y., ASSIGNOR TO FIFTH AVENUE CORSET COMPANY, INC., OF NEW YORK, N. Y., A CORPORATION OF NEW YORK.

FRONT-LACE CORSET.

1,292,491.

Specification of Letters Patent. Patented Jan. 28, 1919.

Application filed March 14, 1917. Serial No. 154,659.

To all whom it may concern:

Be it known that I, JOSEPH LERNOWITZ, a citizen of Rumania, and a resident of the borough of the Bronx, city of New York, county of the Bronx, and State of New York, have invented certain new and useful Improvements in Front - Lace Corsets, of which the following is a specification.

This invention relates to front lace corsets.

The object of the invention is the provision of a tongue for closing the opening in a front lace corset and means whereby the said tongue may be prevented from wrinkling or whereby if wrinkled the wrinkles may be straightened out.

In the accompanying drawings which form a part of this application I have illustrated two forms of my invention, but it is to be understood that the drawings are for illustration only in order that the invention may be the more readily comprehended and that the invention is by no means confined to the two forms shown.

25 In these drawings:

Figure 1 is a front elevation of one of the forms chosen for illustration showing the corset laced and as it is worn;

30 Fig. 2 is a front elevation partly broken away of the corset shown in Fig. 1 illustrating the means for fastening the tongue to the corset body; and

35 Fig. 3 is a front elevation partly broken away illustrating a different form of means for fastening the tongue to the corset body.

Referring to Figs. 1 and 2, the body of the corset 1 is opened in front and is provided with a tongue 2 for closing the opening. Eyes 3 3 are secured to one side of the 40 corset body in front in the usual way and buttons or hooks 4 4 for engagement therewith are secured to a reinforced strip 5 to which the tongue is attached. On the other side of the corset opening is a series of eyelets 6 6 which together with a similar series of eyelets 7 7 in strip 5 are used for lacing the corset by means of an ordinary corset lace 8. A second strip 10 is provided on the inside of the corset body back of but 45 not interfering with the eyelets 6 6 which serves as a means of attachment for the tongue to this side of the body. It is provided with a series of eyelets 11 11 which 50 coöperate with a corresponding series of eyelets 12 12 in the tongue for this purpose

by means of a lace 13. As here illustrated this lace is fastened at the top and bottom of the tongue and loops through two pairs of eyelets 15 15 which are located in the corset body above the strip 10.

60 In the form illustrated in Fig. 3 the strip 10 is omitted and two pairs of eyelets 18 18 replace the series of eyelets 12 12 in the tongue, the lace 13 extending through these eyelets and looping through the eyelets 15 15 in the corset body. Aside from this the two illustrated forms are identical.

The tongue is preferably made of gauze and reinforced by a steel 16. It is of a width such that when the corset is put on 70 and laced it will cover the opening between the sides of the front of the corset body and when perfectly smooth its eyelets 12 12 of Figs. 1 and 2 will not be overlapped by eyelets 11 11 of the strip 10 and in Fig. 3 75 the eyelets 18 18 will not be overlapped by the eyelets 15 15 of the corset body.

In considering the use of this invention it should be borne in mind that in the ordinary putting on and adjusting of a corset 80 the buttons or hooks and eyes along the front steels of the corset are fastened together before the corset is laced. The corset when thus fastened together preferably fits the figure easily. The corset is then laced 85 and the figure drawn to the desired contour as far as conditions permit. In this lacing of the corset the opening between the sides of the corset provided with the lacing eyelets is considerably decreased.

90 The same method is pursued in putting on a corset embodying my invention but as the corset is a front lace corset in lacing the corset after the buttons or hooks 4 4 and the eyes 3 3 have been fastened together it 95 is apparent that unless means are provided whereby the looseness of the tongue can be taken up the tongue will become wrinkled and be a source not only of discomfort but of faulty appearance. To obviate this difficulty either the wearer while lacing the corset by means of the lace 8 can keep the lacing 13 taut or after the corset has been laced can straighten the tongue by means of the said lacing.

100 The corset is taken off in the usual manner by loosening the lace 8 and unclasping the buttons or hooks 4 4 and the eyes 3 3.

105 The foregoing detailed description has been given for clearness of understanding 110

and no undue limitation should be deduced therefrom but the appended claims should be construed as broadly as permissible in view of the prior art.

5. What I claim as new and desire to secure by Letters Patent of the United States is:

1. In a corset, the combination of a corset body opening in front, a tongue for closing the opening, means for lacing the corset, 10 means for removably connecting the tongue with one side of the corset body in fixed relation therewith, and means for movably connecting the tongue with the other side of the corset body whereby the tongue may be 15 laterally extended substantially its full width when the corset is laced, substantially as described.

2. In a corset, the combination of a corset

body opening in front, a tongue for closing the opening, clasps having one set of members attached to the corset body and the co-operating set of members attached to the tongue, means for lacing the corset operating between the tongue and the corset body, and means for connecting the tongue with the corset body whereby the tongue may be laterally extended substantially its full width when the corset is laced, substantially as described.

Signed at New York, N. Y., this ninth 20 day of March, 1917.

JOSEPH LERNOWITZ.
